ENGINE STARTING MECHANISM

Romeo M. Nardone, East Orange, N. J., assignor
to Eclipse Aviation Corporation, East Orange,
N. J., a corporation of New Jersey

Application April 22, 1935, Serial No. 17,710

2 Claims. (Cl. 192—54)

The present invention relates to starting apparatus for internal combustion engines, and more particularly to engine starters of the inertia type embodying an inertia member adapted for high speed rotation.

One of the objects of the invention is to provide in an engine starting mechanism of the inertia type, novel means whereby the acceleration of the inertia member and the imparting of the energy stored in said member to a member of the engine to be started may be controlled.

Another object is to provide in engine starting mechanism of the inertia type, novel ignition current supply means for the engine being started adapted to be controlled simultaneously with the imparting of the energy from the inertia member to the engine member above referred to.

Another object is to provide novel control means embodying a unitary structure wherein the above functions may be controlled from a single control point, as for example, from the instrument panel of an aircraft.

A further object is to provide an ignition current supply device embodying novel means for controlling the same.

A still further object is to provide novel means for controlling the torque transmitting capacity of the elements which connect the driving and driven parts of the starter.

The above and other objects and advantages will appear more fully hereinafter from a consideration of the detailed description which follows with reference to the accompanying drawings, wherein is illustrated one embodiment of the invention. It is to be expressly understood, however, that the drawings are for the purpose of illustration only, and are not to be construed as a definition of the limits of the invention, reference being had for this purpose to the appended claims.

In the drawings, wherein like reference characters refer to like parts throughout the several views,

Fig. 1 is a view in elevation, with parts broken away and parts in section, of starting mechanism embodying the present invention;

Fig. 2 is a sectional view of the friction clutch shown in Fig. 1, but on a larger scale, and with the clutch shown in a different position;

Fig. 3 indicates an alternative arrangement for the magneto of Fig. 1; and

Fig. 4 is an alternative arrangement for the control linkage.

Referring to Figs. 1 and 2, the starter mechanism comprises a housing including a flanged inner portion 4 adapted to be attached to the engine casing 5. Similarly attached to the outer face of flanged member 4 is a housing member 6, having an annular face 7 which constitute the means for attaching in any desired angular position, a handcrank housing 8, in parallelism with a motor housing 9.

Rotatably mounted in the handcrank housing 10 is a shaft 10 which carries on the end thereof that projects outwardly from said housing a sleeve adapted to be engaged by the usual handcrank (not shown).

Fixedly secured to the inner end of shaft 10 is a bevel gear 13 which meshes with a bevel gear 14 that is preferably splined to the hub extension 15 of a spur gear 16, the gears 14 and 16 being held against movement with respect to the housing member 6 by engagement with oppositely facing annular surfaces of the doubly counter-bored boss 17 of the housing member 6. A retaining nut 18, threaded onto extension 15, holds gears 14 and 16 against bearings 19 and 21, respectively, located in the counter-bored portions of the boss 17. A pinion 22 and hollow shaft 23 connect gear 16 with a barrel 24 which is rotatably mounted, as by means of ball bearings 26 and 27, in the flanged housing member 4. The closed end of barrel 24 is provided with a flange 28 from which extend three tubular sleeves 29 one of which is shown in section in Fig. 1. Each of these sleeves which are spaced at intervals of 120° around the inner face of flange 28 is pressed into a counter-bore in said flange, and is secured to a retaining ring 31. Screws 32 pass through the sleeves and are threaded into flange 28. Ball bearings 33 are mounted on these sleeves and rotatably support three planetary gears 34, one of which is shown in section, and one in elevation.

Rigidly secured to the face of the flanged housing member 4 is a double annular gear 36 which surrounds and meshes with the twin sets of planetary gears 34. Each of the latter's gears 45 is in mesh with a sun gear 38 both of which are rotatably mounted on the hollow shaft 23, and one of said sun gears is formed integrally with a flange fastened to a spur gear 39 which is likewise rotatably mounted about the shaft 23, concentric therewith.

In engagement with spur gear 39 is a pinion 41 that is formed integral with the inner end of a shaft 42. The housing member 6 is provided with a hub 43 concentric with the longi-

tudinal axis of shaft 42 and positioned in said hub are ball bearings 44 which rotatably support the hub of a flywheel 46 adapted to be drivably connected with the shaft 42.

5 A booster magneto having a rotor 48 is mounted in the housing 49 connecting through an intermediate gear housing 51 with the housing portion 6 of the starter and novel means are provided for driving said magneto and rotor 48 from the flywheel 46.

10 This drive includes clutch elements 53 and 54, a sleeve 56 integral with clutch element 54, a second sleeve 57 concentric therewith and terminating in a splined portion 58, and a bevel gear 59 splined to the splined portion 58 of sleeve 57, and meshing with bevel gear 13.

15 A spring 61 normally holds clutch elements 53 and 54 disengaged, but yields when engaging pressure is applied through a yoke 62 held fast to 20 a sleeve 63 slideable through housing 51 to a limited extent by means to be described.

25 The energy of the rotating flywheel 46 is imparted to the usual starter jaw or driving member 40 adapted to mesh with, but normally out of engagement with, a similar jaw 45 formed on the end portion 47 of the crankshaft of the engine to be started, or an extension thereof. A yieldable clutch is interposed between the starter jaw 40 and barrel 24, which latter, during the 30 starting operation, is driven by the flywheel through the train of gearing described above.

35 In the form shown, the clutch mechanism comprises a plurality of plates 139 in interleaving and frictional engagement one with the other. One half of said plates are splined to the inner surface of the surrounding barrel 24, closely adjacent the closed end of the latter. Alternating with the discs that are splined to the barrel, are the remaining half of the discs which have 40 splined engagement at their inner peripheries with the outer surface of a nut 138. A rimmed annular plate 141 operatively engages the outer disc of plates 139. An annular spacer 142 bears against plate 141 and transmits to the latter 45 the pressure of a plurality of coil springs 143 which have operative engagement at their outer ends with a clutch adjusting nut 154 threaded into the outer end of barrel 24. Preferably springs 143 are maintained in spaced relation by 50 means of suitable posts 155 which project inwardly from a disc 153, contacting with the inner face of said nut 154. Threaded within nut 138 and adapted for rotary movement therewith and longitudinal movement relative thereto, is a 55 shaft 156 provided with splines at its outer end to receive the interiorly splined tubular portion 35 of starter jaw 40.

60 It is a known fact that the torque transmitting capacity of the friction disc clutch in starters of this character is subject to variation due to change in temperature, change in amount of lubricant between discs, and also depends on the smoothness or roughness of disc surfaces. The present device tends to correct for these 65 variables and retain a given clutch capacity substantially constant, in that the value of the clutch torque is made to depend not only on the force exerted on the pack by springs 143, but also on the angle of the screw thread on 70 shaft 156 and nut 138. When torque is applied to barrel 24, this torque is transmitted to nut 138 through discs 139 and forces screw shaft 156 to the left until the shoulder 145 contacts split washer 146. This same torque between 156 and 75 138 tends to separate the two members, urging

nut 138 to the right against washer 140 backed up by barrel 24 and tending to force spacer 142 to the left through washer 146 against the force of the clutch springs. The resultant spring force on the pack 139 gives the required clutch capacity.

Under certain given conditions, the above resultant spring force on the clutch will give a definite torque capacity. If, say, the discs are dry, the same force will tend to increase the torque capacity. When such a tendency to increase occurs, the jacking action between the screw and nut increases, thus relieving the pack of more of the spring force, and thus offsetting the tendency. The opposite also holds true. If torque capacity tends to decrease, screw action diminishes, thus offsetting the latter tendency. In other words, any tendency toward departure from the originally established capacity is promptly counteracted.

20 The usual meshing rod 157 slidably extends through shaft 156, and jaw 40, said rod being provided intermediate its ends with a shoulder which normally engages the inner end of shaft 156. Surrounding the end of rod 157 is a spring 25 158 which bears at one end against the inner face of starter jaw 40 and at its opposite end against the threaded shaft 156. Preferably the latter is provided with a recess into which a portion of spring 158 extends. The starter jaw 30 is maintained on meshing rod 157 by means of a nut 159 threaded onto the outer end of said rod. To the opposite end of meshing rod 157 there is pivotally connected a lever arm 160 which is preferably constructed in two parts movable in relation one to the other and corresponding respectively to the parts indicated by reference characters 122 and 114 in the drawings of the Lansing Patent No. 1,952,263, granted March 27, 1934, one of said parts being keyed to a rock 40 shaft 161 corresponding to rock shaft 116 of said Patent No. 1,952,263. One end of shaft 161 projects exteriorly of housing 6 and carries a bell crank 162. A coil spring 163 surrounds rod 161, within the housing 6, and one end of said spring 45 is connected to lever arm 160 while the opposite end (not shown) is anchored in a boss of the housing, the spring being so disposed as to act through rod 157 and nut 159 to maintain starter jaw 40 out of mesh with the engine jaw 45.

50 It is intended to control both the energization of motor 9 and the engagement of clutch elements 54 and 53 from a single point, and to this end the sleeve 63 receives a rod or link 201 pivoted at one end to bell crank 162 and at the other end to one arm of bell crank 203, and also having a flange 204 normally engaging one end of sleeve 63. A second link 206 is connected at one end to the second arm of bell crank 203 and passes into the housing 207 containing the 60 normally open switch which controls flow of current to motor 9.

55 The operation is as follows: The cockpit-controlled rod 200 is actuated to swing bell crank 162 and rock shaft in a direction to pull link 65 201 to the left, as viewed in Fig. 1. This action has no effect upon clutch rod 157 for the reason that only one of the elements of the two part lever 160 is keyed to the shaft 161, the mounting of the parts being such as to permit this 70 relative movement in one direction as in Patent No. 1,952,263 above referred to. Likewise, this first movement of rod 201 has no effect on clutch yoke 62, but it does affect the switch actuating parts 203 and 206; in fact, it pulls link 206 75

downward sufficiently to close the circuit to motor 9 through the switch 207, whereby flywheel 46 is caused to turn with motor shaft 11, due to the connecting one-way clutch 12. The links 5 200, 201, and 206 are retained in the switch closing position, just described, until such time as the flywheel 46 has acquired the necessary speed, whereupon the movement is reversed, causing three results substantially simultaneously: first, 10 the reopening of switch 207 (deenergizing motor 9); secondly, closure of clutch 53, 54; and thirdly closure of clutch 40, 45, the former by action of flange 204 on sleeve 63, and the latter by action of shifter fork 160 on rod 157.

15 When the engine "starts" (i. e., engine member 45 overruns member 40) springs 161 and 61 become effective to return rods 157 and 201 to the normal positions shown in Fig. 1, the clutch elements 40 and 53 being disengaged by the same 20 action. Switch 207 remains unaffected by this latter movement of rod 201, due to the "lost-motion" clearance indicated at 210.

There is thus provided novel starting apparatus and control means therefor, whereby the 25 acceleration of the inertia member or flywheel, the transfer of the energy stored in said flywheel to the engine to be started, and the supply of ignition current to said engine may be controlled in proper sequence from a single point.

30 The apparatus is simple in construction and arrangement of parts, which are relatively few, and requires only a single mechanical control, adapted to be mounted within ready access of the operator.

35 While only one embodiment of the invention has been described and illustrated, various changes in construction, arrangement and substitution of parts may be made without departing from the scope of the invention.

40 For example, if the motor drive is not needed in certain installations, the magneto may be transferred to a position of alignment with flywheel 46, as shown in Fig. 3, and driven through the speed reducing gears 224, 226, 227 and 228, 45 and the shafts 229 and 230 connected to the gears 224, and 228 respectively. The drive as shown also includes cone clutch elements 232 and 233 normally held apart by a spring 234 and engageable by actuation of yoke 236, shifter rail 237 50 and actuator 238, the latter on a rock shaft 239 movable by linkage in the manner heretofore indicated in describing Fig. 1. In place of the linkage shown in Fig. 1, that illustrated in Fig. 4, may be employed and is in fact preferred. In 55 this preferred construction the rod 201' is directly in line with the meshing rod 157 and connects therewith through one end, through a lost-motion connection 211, and the outer end of the rod passes through the switch housing 201' containing the switch mechanism corresponding to that within the housing 201 of Fig. 1 and including a pair of stationary current conducting terminals 212 and 213 controlling the flow of current to the motor 9, the circuit being normally open at this point due to the action of 60 compression spring 215 in holding the movable switch plate 214 in the "open circuit position". Also mounted on rod 201' is a sleeve 63' and a clutch actuating yoke 62' corresponding respectively to the elements 63 and 62 of Fig. 1, except 65 that the yoke 62' contacts the clutch element 54' and moves said element to the left to complete the drive from shaft 48' to the magneto 49; the clutch elements 53' and 54' being normally held apart by the spring 61' just as the corresponding elements 53 and 54 of Fig. 1 are held apart by the spring 61. A third compression spring 163' abuts the housing 6 at one end, and a collar on rod 157 at the other end, and has a function similar to that of the spring 163 of Fig. 1, namely, that of tending to maintain the engine engaging member 40 in the non-driving position indicated. In addition to this function spring 163' acts upon the pin 217 of the lost-motion connection 211 to maintain the rod 201' in the neutral position indicated, and in this function it cooperates with the spring 215. The rod 201' has a means 218 at its outer end for manual or other operation by direct engagement therewith or through a connection from this element 218 to the cockpit of the plane. 20 In operation this rod is first pulled to the right to compress spring 215 and close switch 214 to cause energization of the motor 9 and acceleration of the flywheel 46. This movement of the rod to the right has no effect upon the meshing rod 157 due to the lost-motion connection 211. Likewise it has no effect upon the clutch 53', 54' as the rod slides freely within the sleeve 63'. When the flywheel 46 has acquired the necessary speed, rod 201' is moved to the left a 30 sufficient distance to cause three results substantially simultaneously, the said three results being the same as previously described in connection with the arrangement shown in Fig. 1. In producing these three results, namely, the 35 opening of switch 214, engagement of clutch members 53', 54' and also the engagement of clutch members 40 and 45, spring 215 facilitates reopening of the switch 214, collar 204' actuates sleeve 63' and yoke 62', and pin 217 engages 40 and actuates meshing rod 157 which in turn actuates member 40 through the connections indicated in Fig. 1 but omitted in Fig. 4. When the engine starts, the operator releases the pressure exerted on the rod 201' and the parts return 45 to the relative positions indicated heretofore.

What I claim is:

1. In a starter drive having a preset friction clutch controlling the amount of torque transferable to the part to be driven, means for regulating the clutch setting comprising a set of clutch engaging springs, a threaded element having splined engagement with a part of said clutch, a thrust element for transmitting the thrust of said springs to the clutch, and a second threaded element coacting with the first to vary the effectiveness of said thrust element with respect to said clutch. 50
2. In a starter drive having a preset friction clutch controlling the amount of torque transferable to the part to be driven, means for regulating the clutch setting comprising a set of clutch engaging springs, a thrust element for transmitting the thrust of said springs to the clutch, an internally threaded sleeve rotatable with said clutch and means threaded within said sleeve to vary the distance between said sleeve and thrust element and thereby vary the effectiveness of said thrust element with respect to said clutch. 60

ROMEO M. NARDONE.
